UNITED STATES PATENT OFFICE.

ALFRED E. ARCHAMBEAU, OF MARQUETTE, MICHIGAN.

BOOT.

1,250,940.

Specification of Letters Patent. Patented Dec. 25, 1917.

Application filed January 15, 1917. Serial No. 142,410.

To all whom it may concern:

Be it known that I, ALFRED E. ARCHAMBEAU, a citizen of the United States, residing at Marquette, in the county of Marquette and State of Michigan, have invented a certain new and useful Improvement in Boots, of which the following is a full, clear, concise, and exact description, reference being had to the accompanying drawings, forming 10 a part of this specification.

My invention relates to boots and shoes, and has for its object the provision of an improved construction for boots and shoes which are to receive heavy service. More 15 particularly, my invention relates to boots and shoes such as are used for out of door purposes where they are given heavy usage, and wherein it is generally desirable and frequently necessary that thick and warm 20 socks be worn in order to keep the feet warm.

In the general style of shoe as now manufactured the dividing line between the vamp and the upper presents a rigid opening 25 through which the foot of course must be forced in order to enter the vamp portion of the shoe. When heavy socks are worn this rigid opening will not accommodate the foot unless shoes of a size larger than needed 30 are utilized. Under such condition of things the foot when it is finally in place in the vamp is not provided with a well fitting shoe, and inconveniences to the wearer are caused.

35 In accordance with my invention I make this rigid dividing line between the vamp and the upper of a yielding nature. My invention further contemplates that the tongues of the boots or shoes of this nature 40 which are usually sewed to the two adjacent free flaps of the upper be made of a yielding material, preferably thin rubber, so as to accommodate the foot of the wearer even though increased in size by the use 45 of heavy and thick hosiery. Normally shoes or boots of this character have to be purchased generally of a size too large to properly fit the wearer if the unyielding tongue as now applied is used.

50 My invention has these and other objects in view, all as more clearly apparent from the detailed description of several specific forms of carrying out my invention which I will now set forth in connec-

tion with the accompanying drawing, in 55 which—

Figure 1 is a perspective view of a boot constructed in accordance with my invention;

Fig. 2 is a sectional view thereof;

Fig. 3 is a view showing my improved device as applied to a shoe, and

Fig. 4 is a fragmentary view showing my invention as applied to a rubber vamp.

In the structure shown in Figs. 1 and 2 65 the boot has the vamp portion 1 and the upper 2, this being sewed together along the line 3. This line 3 instead of being continuous in a more or less straight line about the upper is extended to form a loop 70 4 so as to provide flap portions 5 forming part of the vamp, which are separable when putting the boot on or taking it off. The two adjoining flaps 6 and 7 of the upper, as well as the adjoining tongues or flaps 5 are 75 then drawn together by a resilient tongue 8, which resilient tongue is sewed to the flaps 6 and 7 and the vamp in such a way that the boot or shoe when completed may be waterproof. In accordance with my invention the vamp portion 1 may be either 80 of leather or rubber. If the vamp portion 1 is of rubber then the tongue 8 should be a strip of rubber integral with the vamp, this strip of rubber however being much 85 thinner than the rubber employed in the vamp portion 1, the transition from the thicker to the thinner portion being gradual, thus to provide a yielding instep and tongue strip, all as shown in Fig. 4. In either 90 event the construction affords a substantially water-tight arrangement which is not possible with the present style of thin leather tongues. The shoe may then be laced through the agency of holes 9 as is customary. Fabric 10 of a yielding resilient nature may be employed as a backing for the tongue 8 when so desired.

It will thus be seen that the cut-away portion as shown at 4 permits a separation of the vamp at the point of the arch when such separation is desirable in putting the shoe on or taking it off. Furthermore, the resilient water-tight tongue draws the two opposing flaps of the boot or shoe together.

From what has been thus described the nature of my invention will be readily clear to those skilled in the art.

Having however thus described two forms which my invention may take, what I claim as new and desire to secure by Letters Patent is:

- 5 1. A boot or shoe of the character described having a vamp portion and an upper portion, the forward part of the vamp over the instep being cut away below the usual vamp top line to form yielding flaps
- 10 over the instep, the upper portion having a forward extension extending into said cut-away part of the vamp, said forward extension of the vamp having means whereby it may be laced over the instep.
- 15 2. A boot or shoe of the character described having a vamp portion and an upper portion, the forward part of the vamp over the instep being cut away below the usual vamp top line to form yielding flaps
- 20 over the instep, the upper portion having a forward extension extending into said cut-away part of the vamp, said forward extension of the vamp having means whereby it may be laced over the instep, and a
- 25 yielding tongue interposed between the opposing flaps of said upper and vamp.
3. A boot or shoe of the character described having a vamp portion and an upper portion, the vamp portion near the forward portion thereof at its junction with the upper portion being cut away to form yielding flaps, the upper portion extending into said cut away portion, said upper having adjoining flaps and a yielding tongue
- 30 portion interposed between the opposing flaps of said upper and vamp, said vamp being of rubber of a given thickness and said tongue being of rubber of less thickness.
- 35 4. A boot or shoe of the character described having a vamp portion and an upper portion, the vamp portion near the forward portion thereof at its junction with the upper portion being cut away to form yielding flaps, the upper portion extending
- 40 into said cut away portion, said upper having adjoining flaps and a yielding tongue portion interposed between the opposing
- 45 flaps of said upper and vamp, said vamp being of rubber of a given thickness and said tongue being of rubber of less thickness, the two rubber portions being integral.
- 50 5. In a boot or shoe the combination of a vamp portion and an upper portion, said upper portion having opposing flaps and a thin yielding rubber tongue adapted to draw the opposing flaps of the upper toward each other, said vamp consisting of rubber of a substantially greater thickness than said tongue.
- 55 6. A boot or shoe of the character described having a vamp portion and an upper portion, the vamp portion over the forward part of the instep being cut away below the usual vamp top line to form yielding flaps, the upper portion extending into said cut away portion, said upper having adjoining flaps and a yielding tongue portion interposed between the opposing flaps of said upper and vamp.
- 60 7. In a boot or shoe the combination of a vamp portion and an upper portion, the vamp portion being made of rubber of a given thickness, and a yielding rubber tongue extending upwardly from the forward part of said vamp portion, said rubber tongue being of less thickness than said vamp portion.
- 65 8. In a boot or shoe the combination of a vamp portion and an upper portion, the vamp portion being made of rubber of a given thickness, and a yielding rubber tongue extending upwardly from the forward part of said vamp portion, said rubber tongue being of less thickness than said vamp portion, said tongue extending into the vamp portion over the forward part of the instep.
- 70 9. In a boot or shoe the combination of a vamp portion and an upper portion, the vamp portion being made of rubber of a given thickness, and a yielding rubber tongue extending upwardly from the forward part of said vamp portion, said rubber tongue being of less thickness than said vamp portion, said tongue extending into the vamp portion over the forward part of the instep.
- 75 10. In a boot or shoe the combination of a vamp portion and an upper portion, the vamp portion being made of rubber of a given thickness, and a yielding rubber tongue extending upwardly from the forward part of said vamp portion, said rubber tongue being of less thickness than said vamp portion, said tongue extending into the vamp portion over the forward part of the instep.
- 80 11. In a boot or shoe the combination of a vamp portion and an upper portion, the vamp portion being made of rubber of a given thickness, and a yielding rubber tongue extending upwardly from the forward part of said vamp portion, said rubber tongue being of less thickness than said vamp portion, said tongue extending into the vamp portion over the forward part of the instep.
- 85 12. In a boot or shoe the combination of a vamp portion and an upper portion, the vamp portion being made of rubber of a given thickness, and a yielding rubber tongue extending upwardly from the forward part of said vamp portion, said rubber tongue being of less thickness than said vamp portion, said tongue extending into the vamp portion over the forward part of the instep.

In witness whereof, I hereunto subscribe my name this 11th day of January, A. D. 1917.

ALFRED E. ARCHAMBEAU.
